UNITED STATES PATENT OFFICE.

LEWIS I. HAMILTON, OF NEW MADRID, MISSOURI.

COTTON-PICKER.

No. 923,649.

Specification of Letters Patent.

Patented June 1, 1909.

Application filed December 14, 1907. Serial No. 406,455.

To all whom it may concern:

Be it known that I, LEWIS I. HAMILTON, a citizen of the United States, residing at New Madrid, in the county of New Madrid and State of Missouri, have invented new and useful Improvements in Cotton-Pickers, of which the following is a specification.

The invention relates to an improvement in cotton pickers of the pneumatic type, 10 wherein the cotton is picked from the plant and delivered into the storage receptacle entirely by pneumatic action.

The main object of the present invention is the provision of a pneumatic cotton picker in 15 which the cotton is separated from the pods mainly by suction, the construction including an auxiliary device in the use of which the material may be mechanically separated from the pods when necessary.

Another object is the provision of a storage 20 receptacle for the cotton picked by the apparatus, which receptacle is so formed as to provide for the initial separation from the cotton material of the usual refuse accompanying such material.

The invention will be described in the following specification, reference being had particularly to the accompanying drawings, in which:—

Figure 1 is a view in side elevation of a 30 cotton picker constructed in accordance with my invention. Fig. 2 is a plan of the same. Fig. 3 an end elevation of the same. Fig. 4 a plan of the picking bell. Fig. 5 is a vertical sectional view, partly in elevation of the picking bell in position on the picking tube.

Referring particularly to the accompanying drawings, wherein is illustrated a preferred and simple form of the improved apparatus, it will be noted that the operative parts of the machine are supported upon a bed 1 of a wheeled structure 2, as for example an ordinary wagon. The detailed 40 construction of the wheeled support for the apparatus is entirely immaterial so far as the present invention is concerned, it being understood in this connection that the apparatus in commercial form is designed to be drawn lengthwise the field during the picking operation, and that the wagon body may be of any construction desired, the sole requirement being that it avoid injury to the plants over which it is passing.

Secured upon the rear end of the platform 1 is a suction fan 3, which is also of any usual

or preferred construction and except that it should be of a character to create a powerful suction forms no material part of the present invention. The fan is thus preferably, 60 though not necessarily, driven by an ordinary belt 4 from a suitable motor, such as a gas engine 5, though the fan may be geared direct, or otherwise operated if desired. The suction box 6, offset from the fan casing 65 and in open communication therewith, is provided with divergent suction pipes 7 and 8, the former extending laterally of the wagon body, while the latter extends rearwardly and transversely of said body in rear 70 of the fan casing, terminating beyond the side of the body in opposition to the projection of the pipe 8. Picking tubes 9 are connected to the terminals of the respective suction pipes 7 and 8, so that by the arrangement of said pipes described the picking tubes 75 normally project in opposite directions from the wagon body and are capable of an extended sphere of movement on each side and in rear of the wagon body. The 80 picking tubes, which are flexible hose, are of the ordinary form except that they gradually taper from their connection with the suction pipes to their free or outer ends, so that from the free or picking end of each tube the 85 interior diameter gradually increases toward the suction pipes.

The free end of each picking tube is provided with what I term a picking bell, consisting essentially in a bell shaped body 10 90 having a pipe extension 11 to fit within the end of the picking tube and formed beyond said extension to provide a materially enlarged mouth 12. Disposed within the flared portion of the bell is a diametrically arranged 95 frame strip 13 in which is formed a bearing 14 for the reception of a stub shaft 15. The relatively inner end of this shaft is provided with propeller blades 16, while the outer end is formed or otherwise provided with divergent tines 17, forming a fork for engagement with the cotton, as will presently appear.

From the construction described it is obvious that the suction created by the fan 3 will, through the medium of the blades 16, impart 105 a continuous revolution to the stub shaft 15, thereby revolving the fork and constituting the latter in effect a mechanical picker.

Leading from the fan casing 3 in opposition to the suction pipes 7 and 8 is a delivery pipe 18, through which the air drawn 110 from the suction pipes is forced by the fan.

The delivery pipe projects forwardly from the casing in an upward direction, terminating in a downturned delivery end or mouth 19, which directly and centrally overlies a 5 receptacle or cotton receiver 20. The receiver 20 is preferably of cylindrical form and of substantial proportions, the wall of the receiver being formed of wire netting, as clearly apparent from the drawings.

10 Secured upon the forward axle and tongue of the wagon is a semicylindrical platform 21, which projects beyond the wheels and is supported on brackets 22 rising from extensions of the axle. The platform provides a 15 support for the operator when working at the forward end of the apparatus.

In use the wagon is moved longitudinally of the field between the rows, and one or more operators apply the picking bells to the 20 respective ripe pods. The suction will be found sufficient to detach the ripe cotton from the pods and draw the same through the picking tubes 9 into the fan casing and from the latter to the delivery tube 18 and 25 thence to the receiver 20. Practically all the matured cotton will be easily separated by the suction, but in those pods in which the cotton, though desirable for commercial purposes, is not thoroughly ripe or is slightly 30 damp the fork 17 is brought into play, being engaged with such cotton and, by the revolution imparted through the propellers 16 will readily twist or detach the cotton from the pods.

35 The material of which the apparatus is to be constructed, or the size of the various parts, are not important in the present invention, it being contemplated to construct the apparatus of a light substantial character 40 and of a capacity suitable to the requirements of its particular use.

Having thus described the invention what is claimed as new, is:—

1. A cotton picker comprising a wheeled 45 frame, a suction apparatus mounted thereon, and a supporting platform terminally connected to the forward axle beyond the

wheels thereof, said platform resting in advance of the wheeled frame.

2. A cotton picker comprising a wheeled 50 frame, a suction fan mounted thereon, a suction box in communication with the fan, a pipe section leading from said box laterally of the frame, a second pipe section in communication with the box and extending longitudinally of the frame and laterally thereof in opposition to the first pipe section, and suction tubes connected to the respective pipe sections.

3. A cotton picker comprising a wheeled 60 frame, a suction fan mounted thereon, a suction box in communication with the fan, a pipe section leading from said box laterally of the frame, a second pipe section in communication with the box and extending longitudinally of the frame and laterally thereof in opposition to the first pipe section, and suction tubes connected to the respective pipe sections, each of said tubes comprising a flexible member tapering from its connection 65 with the pipe section toward the free end.

4. A cotton picker comprising a wheeled 70 frame, a suction fan mounted thereon, a suction box in communication with the fan, a 75 pipe section leading from said box laterally of the frame, a second pipe section in communication with the box and extending longitudinally of the frame and laterally thereof in opposition to the first pipe section, suction tubes connected to the respective pipe sections, each of said tubes comprising a flexible member tapering from its connection 80 with the pipe section toward the free end, a bell mouth removably connected to the free 85 end of each suction tube, and automatically actuated picking means arranged in said bell mouth.

In testimony whereof I affix my signature in presence of two witnesses.

LEWIS I. HAMILTON.
